RADIOTRANSMITTER MOUNTING

Application filed September 9, 1930. Serial No. 480,800.

Our invention relates to radio transmitters, and particularly to mounting and cushioning means for a transmitter.

An object of our invention is to provide a simple and inexpensive cushion support for a transmitter.

A further object is to provide a cushion support for a radio transmitter including tie-down and guy members.

Still other objects are to provide a simple and inexpensive mounting for a portable radio transmitter in mobile service, such as on a ship; and to utilize simple and easily obtainable materials and devices for securing a portable transmitter in place, so as to avoid damage to the component parts, and to prevent such jarring and vibration as would interfere with the stability of the signaling frequency.

In the operation of radio transmitters, particularly at extremely high frequencies, difficulty has been encountered from vibration, which tends to change the relative position of parts of the circuit in such a way as to alter the frequency of the emitted electrical oscillations. These effects may be due in part to swinging of the antenna, but a substantial portion may be due also to vibration of the generator and its associated elements. Likewise, vibration of the transmitter tube elements at an audible frequency has an influence upon the signals radiated, especially when they are received by the heterodyne method. Vibration and shocks may also cause difficulties in additional ways, such as loosening connections and other parts in the transmitter, and shortening the filament life of the transmitter tube.

Our invention comprises a simple arrangement of cushion members, spring and turn-buckle tie-members and spring and turn-buckle guy-members adapted to support and position the radio transmitter and its containing cabinet with respect to the ship's structure in such a way that the troublesome vibrations and the like, and their effects are eliminated.

Other objects and advantages of our invention will be apparent from the following

description when read in connection with the accompanying drawing; wherein

Fig. 1 is a view in perspective of a transmitter system and cabinet embodying our invention.

Fig. 2 is a view in vertical section of one of the cushion members of our invention, on line $\alpha-\gamma$ of Fig. 3,

Fig. 3 is a perspective thereof; and

Fig. 4 is a plan view of the transmitter and the guy members of our invention.

Referring to the figures, the members of the radio transmitter including the vacuum tube and resonant circuits may be positioned within the sections 1, 2 and 3 of a suitable cabinet or casing. The cabinet is supported upon uprights 4, which may form integral parts thereof. Foot plates 5 are attached to the legs 4 by angle members 6 as shown in Fig. 2. A floor or base frame 7 is provided having the peripheral portions formed of angle bar members 8, with plate members 9 at the corners cooperating therewith. At the respective corners of the frame 7, which is rectangular, are provided rectangular compartments formed within the corners by bent straps 11, secured at their ends to the bars 8. The plates 5 and 9 correspond with these compartments in shape.

The foot plates 5 are also equipped with angle members 12 attached at the edges thereof as shown in Fig. 2. The angle members 12 and 6 may be attached to the foot plate 5 in any convenient way as by rivets or bolts as indicated.

Rubber pads are provided beneath the foot plates 5. A pad of sponge rubber 14 is disposed between each foot plate 5 and floor plate 9 to support and cushion the weight of the transmitter and the cabinet. Between the angle members 12 and the angle members 8, and also between the angle members 12 and the straps 11, are cushions 15, formed of live rubber as distinguished from the sponge rubber utilized for the cushion 14. The cushions 15 serve to center the legs 4 and to support the transmitter and cabinet against side-wise movement. The pads 14 may also be of live rubber, if desired.

Angle or reinforcing plates 16 are also provided and affixed to the upright members 4 at their point of junction with the lower chamber 1. These serve as attachment points 5 for the upper ends of tie members, each made up of a spring member 17, a turn buckle 18 and hook members 19. The tie members are held in diagonal position with their lower ends secured to the angle bars 8.

10 Guy members are also provided on the top of the transmitter cabinet, secured at the corners and adapted to be attached to a ceiling or the under-side of a deck above the transmitter. These also may desirably consist 15 of springs 17, turn buckles 18 and hook members 19 adapted to be attached to fixed bolting plates 21, fastened to the ceiling or over-head deck.

20 In the operation of the device of our invention, the guy members and tie members serve to attach the transmitter cabinet to the ship and provide an elastic support. The rubber cushion members between the foot plates 5 and floor plates 9 serve to prevent 25 the transmission of the rapid vibrations which tend to produce audio frequency variations in the transmitted wave. The tie members hold the transmitter structure tightly to the floor, and prevent displacement 30 of the transmitter during rolling and pitching of the ship. Similarly, the guy members on the top section 3 of the transmitter structure assist in maintaining the relative position between the transmitter and the ship structure during such stresses as occur during rolling or pitching of the ship. The presence of the springs 17 indicated prevents 35 the transmission of troublesome vibrations to the transmitter structure without impairing the security of attachment.

40 The floor plates 9 may rest on the horizontal inner flanges of the angle bars 8 and on supporting plates or blocks 9' of the right thickness in the plane of these flanges. (See 45 Fig. 2). These plates 9' may be made fast to the bars 8.

By our invention we have thus produced a new and useful system of mounting a portable radio transmitter and rendering it shock-proof.

50 While we have shown but a single embodiment of the device of our invention, it is possible to produce other embodiments of the same inventive concept and it is therefore desired that only such limitations shall be imposed upon the appended claims as are stated therein, or required by the prior art.

We claim as our invention:

60 1. A transmitter comprising a casing having a plurality of rigid upright supporting members, a foot plate having flanged edges at the bottom of each upright, a base frame having compartments to receive said foot plates, and bottom cushion members for said foot

plates in said compartments, and auxiliary side cushion members inserted between said flanged edges of said foot plates and the sides of said compartments.

70 2. A transmitter comprising a casing having a plurality of rigid upright supporting members, a foot plate having flanged edges at the bottom of each upright, a base frame having compartments to receive said foot plates, bottom cushion members for said foot plates in said compartments, and auxiliary cushion members disposed between the sides of said compartments and the flanged edges of said foot plates.

75 3. A transmitter comprising a casing having a plurality of rigid upright supporting members, a foot plate having flanged edges at the bottom of each upright, a base frame having compartments to receive said foot plates, bottom cushion members for said foot plates in said compartments, auxiliary cushion members disposed between the sides of said compartments and the flanged edges of said foot plates, and elastic tie members between 80 said casing and said base to hold said foot plates against said cushion members.

85 4. A transmitter comprising a casing having a plurality of rigid upright supporting members, a foot plate having flanged edges at the bottom of each upright, a base frame having compartments to receive said foot plates, bottom cushion members for said foot plates in said compartments, auxiliary cushion members disposed between the sides of said compartments and the flanged edges of 90 said foot plates, elastic tie members between said base and said casing to hold said foot plates against said cushion members, and guy members attached to the top of said casing 95 and to a suitable support.

100 5. Cushioning means for the casing of a transmitter comprising rigid legs, foot plates therefor having upturned edge members, a base frame having rectangular corner pockets with upturned edges, and bottom pads therein for said foot plates, and auxiliary pads between the upturned edges of said foot plates and the upturned edges of said pockets.

105 In witness whereof, we hereunto subscribe our names this 6th day of September 1930.

HERMAN P. MILLER, JR.
EARL G. PORTS.
